MARKING ROLLER

Mark Andrews, Kirkwood, Mo.

Application March 6, 1942, Serial No. 433,619

4 Claims. (Cl. 101—329)

This invention relates to marking rollers, and particularly to marking rollers for the purpose of marking strip stock, such as metal rods, bars, and shapes, although it may be used for many other purposes. It has previously been customary to mark such material with an ordinary rubber stamp or by painting it with a special color. But, these methods have been unsatisfactory for a number of reasons, particularly the amount of time required to apply the proper marking, in fact, previous marking methods have been so unsatisfactory that they have not been fully applied, with the result that many pieces of valuable material are lost, because, unless the marking is given, there is no way of distinguishing different materials which may have identical surface appearance. By the use of my invention, such materials may be fully marked from end to end at negligible cost.

It is the object of the invention to produce a new and improved marking device.

The invention will be better understood upon consideration of the following specification and accompanying drawing, in which

Figure 1 shows a sectional elevation of the device, and

Figure 2 shows a plan view.

The reference numeral 1 indicates a frame made of sheet material, preferably fibre or Bakelite. The two substantially identical frame members are separated by bushings 3, 4, 5 and 6, and the assembly is held together by a rivet 7, which passes through the bushing 3, and bolts 8, 9 and 10 which pass through the bushings 4, 5 and 6, respectively. The bolts and their respective bushings form spacer axles for the wheels 11, 12 and 13.

The wheel 11 carries a rubber type roller or "tire" 14, and a tread 15 of the tire is formed of the printing characters or type. This tire is resilient and detachable by removing the spacer axle 5—9 which is accomplished by merely unscrewing the nut 16. A separate tire is provided for each marking which it is desired to use, and these tires are interchangeable on the roller 11 by the removal of the spacer axle 9—5. In this connection, it may be noted that the bushing 5 may be firmly fitted to the roller 11 or integrally therewith.

The inking reservoir is a felt tire 17 carried by the rubber band 18 to which it is cemented. The members 17 and 18 are detachable from the roller 13 in the same way as the tire 14 is detachable from the roller 11.

The ink is transferred from the reservoir to

the type roller by means of the transfer roller 12 on which is mounted the rubber tire 19 to which is attached the transfer ring 20. While these members are quite durable and seldom need replacement, they may be detached for cleaning purposes by removal of the spacer axle 8—4, and it will be understood that the bushing may be made integral with the roller 12, if desired.

In operation, the ink is applied to the ink reservoir or felt member 17 in liberal quantities. The marking device is held in the hand and dragged over the article to be marked, using the type roller 14—15 as a supporting tire. The reservoir and transfer roller are rotated by contact with the member 15, which is the only member to contact the material being marked. In this manner, strips of material can be marked from end to end very quickly and at low cost.

I claim:

20. 1. A marking device comprising a frame including side plates, a plurality of removable pins extending through said plates and having intermediate axle portions, removable bushings on said axle portions for holding said plates in spaced relation, hub portions fixed on said bushings, and a marking roller, a reservoir roller and a transfer roller, each including a relatively thick inner layer of resilient material for removable frictional engagement with said hub portions, and being detachable with their hubs upon removal of said pins.

2. A marking device comprising a frame including spaced side plates, a pivot pin extending through said plates adjacent one end thereof, a plurality of removable spaced pins extending through said plates, each of said spaced pins including intermediate axle portions, removable bushings on the axle portions of said pins and hub portions fixed on said bushings, a marking roller, reservoir roller and transfer roller mounted on said hubs, each of said rollers including resilient inner portions for frictionally engaging the hubs and surface portions, the surface portion of said rollers being in peripheral contact with each other whereby movement of the marking roller will transmit motion to the transfer and reservoir rollers.

3. A marking device comprising a frame including spaced side plates, a pivot pin for connecting said side plates adjacent one end, a plurality of removable pins extending through said plates, each of said pins including intermediate axle portions, a marking roller mounted on one of said pins, said marking roller including a resilient removable tire portion and an inner hub

portion rotatably mounted on the axle, and means for feeding and transferring ink to said marking roller.

4. In a marking device, a frame constructed and arranged to be held in the hand, a marking roller, a reservoir roller, and a transfer roller carried by said frame in peripheral contact with

each other, whereby movement of the marking roller will cause rotation of the transfer and reservoir rollers, said reservoir roller having a rubber-cored felt-covered tire and said marking roller including a cushioned core removably mounted on a detachable hub portion.

MARK ANDREWS.
